(57) **CLAIM**

The ornamental design for a folding dining chair, as shown and described.

DESCRIPTION

FIG. 1 is a front side perspective view of a folding dining chair showing my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken line in FIGS. 1-6 illustrate portions of the folding dining chair that form no part of the claimed design.

1 Claim, 6 Drawing Sheets
